UNITED STATES PATENT OFFICE

2,115,850

OIL BURNER

Clayson R. Hammond, Salem, Oreg., assignor of
fifty-five percent to Herbert E. Foster, Salem,
Oreg.

Application June 23, 1936, Serial No. 86,855

7 Claims. (Cl. 158—56)

This invention relates to oil burners and the like and is particularly adapted to be used in furnaces, boilers, cook stoves, in fact, any place where heat is required.

5 The primary object of this invention is to introduce hydrogen and oxygen in the form of steam together with the hydrocarbon contained in the low grade fuels, expanding both within a heated chamber prior to expelling the mixture in 10 the form of gas from the burner jets at which time additional secondary air is induced by the flow of the gas from the jets prior to combustion.

Another object of the invention is to provide 15 a burner having no moving parts, but at the same time completely vaporizing the fuel prior to combustion.

A further object of the invention is to prevent 20 carbonization of the fuel within the burner unit itself.

25 Another object is to permit rapid, easy and positive starting of the burner when cold.

A further object is to introduce the proper 30 quantity of steam into the gas mixture by injection.

25 A still further object is to water jacket the fuel nozzle and fuel supply line throughout its length within the fire-box, preventing the fuel supply line and nozzle from carbonizing while delivering fuel to the generating chamber.

30 Another object is to provide a hot spot that will be equal in temperature over its entire surface.

35 A still further object is to build the generating chamber of a low heat conducting material, while the delivery pipes to the burner jets are of a rapid heat conducting material.

Referring to the drawing:

Figure 1 is an assembled side view of my new and improved oil burner.

40 Figure 2 is a sectional plan view taken on line 2—2 of Figure 1, looking in the direction indicated.

Figure 3 is an enlarged sectional view of the 45 generating chamber enclosing the steam and fuel nozzle, with portions broken away for convenience of illustration.

Figure 4 is a sectional view taken on line 4—4 of Figure 2, looking in the direction indicated.

Figure 5 is a sectional view taken on line 5—5 50 of Figure 2.

Figure 6 is a sectional view of the fuel nozzle having a water jacket surrounding the nozzle and fuel line.

Figure 7 is a perspective view of the vaporizing 55 trough removed from the generating chamber.

Figure 8 is a sectional view of the generating chamber taken on line 8—8 of Figure 3, looking in the direction indicated, illustrating the fuel and steam nozzles.

In the drawing

1 is the generating chamber having a removable cap 2 on its one end and tubes 3 and 4 on its opposite end, turning downward in the curved portion 4A having a horizontal section of tube 5, forming a lower flame section, curved upwardly at 6 and terminating in the horizontal portion 7 forming an upper flame section with a closed curved end 8. The generating chamber housing 1 is made from a material of low heat conductivity while the tubes 3 and 4 throughout their entire length, are of high heat conducting material. The cap 2 has nipples 9 and 10 on its outer end and a bell portion 11 extending inwardly within the generating chamber 1. Bell 12 also is an integral part of the cap 2 and extends in beyond and within the bell 11, as best shown in Figure 3. The hollow tube 13 surrounds the fuel line 14 and provides a water space 15 for surrounding the fuel line 14 clear to the end 16 of the nozzle 17. This water jacket is for the purpose of preventing carbon accumulation at the end 17 or the nozzle of the fuel line 14. The whole assembly is longitudinally adjustable within the nipple 9 and the inner bell 12 or is adjusted to any position by the stuffing box 19. The fuel line 14 receives its fuel from the control valve 20 while the water jacket 13 receives a water supply from the valve 21.

35 In order to introduce steam within the generating chamber 1 together with the fuel from the nozzle 17, a boiler 22 is provided. The boiler 22 consists of an outer coil 23 starting with the tube 24 leading from the connection 25 of the water jacket 13. The opposite lead 26 of the outer coil 23 terminates in an inner or smaller coil 27, coiled in a downward spiral, terminating in the tube 28 which is packed into the nipple 10 by a suitable connection or stuffing box 29. The nipple 10 has a passage 30 terminating in a nozzle 30A for 40 discharging the steam past the bell 12 and mixing it with the fuel from the nozzle 17. The coils are supported on a plate 27' carried by rods 28' depending from the cap 2. A vaporizing trough or hot spot is shown at 31 extending along the 45 lower side or bottom of the generating chamber. This trough is made from a high heat conducting material so that the heat is evenly distributed over its entire surface. The heat trough 31 terminates in a cylindrical sleeve 32 which fits 50 55

snugly within the heat chamber 1 within the cap 2. The heat chamber and the cylindrical portion 32 fit against the gasket 33 within the cap 2, the whole assembly being locked in position by the cap screw 34. The cap screw is threaded within the chamber 1. The cap 2 has a slot 35 providing adjusting means against the gasket 33. The heating trough 31 is an important part of this invention because of its high heat 5 conductivity.

To start the burner, a pan 36 having a suitable wick therein is saturated from the fuel oil which is supplied down through the pipe 37 from the fuel nozzle 17, supplying heat to the generating chamber. As the heat from the burning fuel in the pan 36 starts the generation of vapor in the generating chamber, a portion of such vapor will flow through the tube 37 and be ignited from the flame of the burning fuel in the pan 36 for generating 10 steam in the coils of the burner. The amount of water admitted into the boiler will be controlled automatically by the pressure generated within the chamber 1 and pipes 3 and 4 leading to the burner jets indicated at 40. The main object of 15 this invention is the mixing of the steam from the nozzle 30A with the fuel from the nozzle 17 after which this mixture is delivered to the burner jets 40.

Referring to Figure 4, part of the burner jets 20 are directed against the generating chamber. An angle, shown in dotted position by numeral 41 resting on top of the generator, provides a means of controlling the amount of heat applied to the generator. The revolving of the same to the 25 right, referring to Figure 4, upon the top of the generator traps the flames 42 within the space 43 directing a greater amount of heat against the generator 1. By revolving the angle to the left it will allow the flames to escape past the generator 30 more easily thereby applying less heat. In other words, the angle iron 41 resting longitudinal upon the top surface of the generator provides a control for the amount of heat to be absorbed by the generating chamber. The flames 44 are directed 35 past one side of the heat chamber, while the flames 45 are directed upward. The flames 42 and 44 may be directed towards the left or reversed as shown in Figure 4, their direction depending upon the type of fire box that the burner is installed in. 40 Having thus described my invention, I do not 45 wish to be limited to the particular form of construction as my invention is adaptable to other mechanical embodiments still coming within the scope of the claims to follow.

50 55 What is claimed to be new is:

1. An oil burner including a vaporizing chamber, a cap for one end thereof, a nipple carried by the cap extending inwardly from the end wall of the cap toward and into the vaporizing chamber, a fuel pipe terminating in a nozzle opening into the vaporizing chamber, and a water jacket surrounding the fuel pipe to the point of the nozzle, said water jacket and fuel pipe being adjustable longitudinally of the nipple.
- 60 65 2. An oil burner including a vaporizing chamber, a cap for one end thereof, a nipple carried by the cap said nipple extending inwardly from the

end wall of the cap, a fuel pipe terminating in a nozzle, a water jacket surrounding the fuel pipe to the point of the nozzle, said water jacket and fuel pipe being longitudinally of the nipple, and a vaporizing trough having an annular portion 5 surrounding the nozzle and nipple and extended longitudinally of the generating chamber as an upwardly opening section, the vaporizing trough being of high heat conductivity.

3. An oil burner including a generating chamber, a cap closing one end thereof, a nipple carried by the cap, a fuel pipe movable longitudinally of the nipple and terminating in a nozzle, a steam inlet passage formed in the cap at one side of the nozzle, a steam generating coil supported by the 10 cap and communicating with the steam inlet, means for admitting water to the coil, and a connection from the generating chamber to and beneath the coil, said connection terminating as a burner to generate steam in the coil.

4. An oil burner including a generating chamber, a cap for one end thereof, a nipple carried by the cap, a steam inlet formed in the cap, a fuel pipe terminating in a nozzle, a water jacket for the fuel pipe, a coil carried by the cap and subject to heat from a burner fed from the generating chamber, a communication between the coil and steam inlet, and a communication between the coil and the water jacket about the fuel pipe.

5. An oil burner including a generating chamber, a cap for one end thereof, a nipple carried by the cap, a steam inlet formed in the cap, a fuel pipe terminating in a nozzle, a water jacket for the fuel pipe, a coil carried by the cap and subject to heat from a burner fed from the generating chamber, a communication between the coil and steam inlet, and a communication between the coil and the water jacket about the fuel pipe, said water jacket and fuel pipe being movable as a unit longitudinally of the nipple.

6. An oil burner including a generating chamber, a water jacketed fuel inlet at one end thereof, a steam coil supported by the generating chamber, means for supplying the steam coil from the water jacket of the fuel inlet, a steam inlet leading from the coil to the generating chamber, a vaporizing trough arranged in the generating chamber, and a gas outlet from the trough to a burner terminal arranged for heating the coil.

7. An oil burner including a generating chamber, a water jacketed fuel inlet at one end thereof, a steam coil supported by the generating chamber, means for supplying the steam coil from the water jacket of the fuel inlet, a steam inlet leading from the coil to the generating chamber, a vaporizing trough arranged in the generating chamber, and a gas outlet from the trough to a burner terminal arranged for heating the coil, the generating chamber being extended to form a lower and an intermediate set of burners disposed beneath the generating chamber, a part of the intermediate set of burners directing the flame toward the generating chamber and the remaining part of said burners directing the flame laterally of the generating chamber.

CLAYSON R. HAMMOND.
